UNITED STATES PATENT OFFICE.

WILLIAM T. NICHOLLS, OF WELLSBURG, WEST VIRGINIA.

TILE.

No. 926,282.

Specification of Letters Patent.

Patented June 29, 1909.

Application filed April 30, 1907. Serial No. 371,041.

To all whom it may concern:

Be it known that I, WILLIAM T. NICHOLLS, of Wellsburg, Brooke county, West Virginia, have invented a new and useful Improvement 5 in Tiles, of which the following is a full, clear, and exact description, reference being had to the accompanying drawings, forming part of this specification, in which—

Figure 1 is a perspective view illustrating 10 my invention; Figs. 2, 3 and 4 are plan views showing my invention applied to tiles of different shapes; and Fig. 5 is a perspective view showing another feature of my invention.

15 My invention has relation to tiles, and is particularly designed to provide a tile having means for more effectually bonding it in cement, concrete, mortar or other setting.

In accordance with my invention, I provide 20 the tile at one or more of its edges, preferably at all of its edges, with a series of irregular projections, which are designed to contact with similar projections on adjacent tiles, the spaces between the projections

25 forming openings through which the cement or mortar which forms the joints between adjacent tiles is more effectually bonded to that beneath or behind the tiles. In connection with the spacing feature, it is proposed to 30 secure the maximum degree of spacing with the minimum length of projections. This is accomplished by having the spacing projections on each tile arranged to abut the corresponding projections on adjacent tiles, 35 whereby the length of each projection is only one-half of the width of the space. The advantage of the relatively short projections is that they are less likely to become broken in storage, transportation and handling than 40 where the spacing projections are as long as the width of the space.

Another feature of my invention consists 45 in providing a tile having its inner or seating face formed with a series of undercut projections which are disposed at an angle so that when seated in the mortar or other setting, they will act to resist movement of the tile in any direction.

Referring to the drawing, the numeral 2 of 50 Figs. 1 and 2 designates rectangular tiles each of which has its edges formed of a series of irregular projections 3. These projections may be of any desired form, but should be of such shape, or spaced in such an irregular 55 manner, that those upon adjacent tiles will not interfit with each other. These pro-

jections form separators for the tiles, and the openings between them form spaces through which the mortar or cement at the joints 4 is united with and bonded to the underlying 60 layer or bed 5. These projections may extend the full thickness of the tile, but preferably are restricted to the inner edge portions so that they will not be visible from the 65 surface.

My invention is applicable to tiles of all angular forms, thus, in Fig. 3 I have shown it as applied to a hexagonal tile, and in Fig. 4 to a tile of triangular form. This feature is not necessary to tiles of circular or oval 70 form, since with such tiles sufficient space is formed between them by reason of their shape to effect the necessary bonding.

The projections on the edges of the tiles not only serve to space the tiles for the purpose above described, but they also form positive means for anchoring the tiles in the cement in which they are set, whereby ribs or projections, or other anchoring means, 75 may be dispensed with.

In Fig. 5 I have shown the invention applied to a tile of angle form. This figure also shows a second feature of my invention, viz., the provision of a series of undercut ribs or projections 6 on the seating faces of 80 the tile which extend at an angle sufficient to enable them, when embedded in the mortar or other setting, to resist the movement of the tile in any direction. This feature of 85 my invention, while particularly useful in connection with tiles of angle form, may be used on tiles of all forms, either with or without the edge projections.

The advantages of my invention will be 90 readily appreciated by those skilled in the art, in view of the difficulty which has heretofore been experienced in properly bonding 95 tiles of angular form.

What I claim is:

1. As a new article of manufacture, a tile 100 having a finished front face and provided upon its edges with integral projections flush with the back of the tile and terminating short of the finished face, said projections being irregularly spaced and adapted to 105 abut the projections of adjacent tiles, substantially as described.

2. As a new article of manufacture, a thin 110 facing slab having a finished front face, and provided throughout its peripheral edge with spacing projections set back from the front face and irregularly spaced and ar-

ranged to abut the projections of adjacent tiles, substantially as described.

3. A tiled surface composed of thin facing slabs having their adjacent edges spaced 5 from each other by means of integral abutted projections set back from their front faces, substantially as described.

4. A tiled surface consisting of thin facing slabs set in a plastic adhesive and separated 10 from each other by integral, abutted projections set back from the surface to provide intervening spaces for the adhesive and to bond such adhesive to that which underlies the tiles; substantially as described.

15. 5: As a new article of manufacture, a tile having a finished front face and provided upon its back with an oblique rib, and having its edges provided with spacing projections flush with the back of the tile and terminating short of the front face thereof, said 20 projections being irregularly spaced and adapted to abut the projections of adjacent tiles when set up, substantially as described.

6. As a new article of manufacture, a tile 25 having a finished front face, the back of the tile being provided with a series of oblique ribs having corresponding longitudinal edges undercut and their outer faces beveled from their undercut edges to the back face of the 30 tile, the edges of the tile being provided with

spacing projections flush with the back of the tile and terminating short of the front face thereof, said projections being irregularly spaced and arranged to abut the projections of adjacent tiles, substantially as 35 described.

7. A tiled surface having thin facing slabs provided upon each edge with spacing projections set back from the front faces thereof and abutting the projections of adjacent slabs, whereby the latter are spaced 40 twice the length of each projection, and a plastic adhesive between the edges of the slabs and covering and concealing the projections, substantially as described.

45 8. A tiled surface made up of spaced thin facing slabs, each slab having at least one edge provided with spacing projections set back from the front face and abutting the spacing projections of adjacent slabs, the length of 50 each spacing projection being substantially one-half the width of the space between adjacent slabs, substantially as described.

In testimony whereof, I have hereunto set my hand.

WILLIAM T. NICHOLLS.
